UNITED STATES PATENT OFFICE.

JOSEPH ZUBATY, OF FLINT, MICHIGAN, ASSIGNOR TO A C SPARK PLUG COMPANY, OF FLINT, MICHIGAN, A COMPANY OF MICHIGAN.

ILLUMINATED INSTRUMENT PANEL.

Application filed February 23, 1927. Serial No. 171,602.

This invention relates to illuminating means for instrument panels. In my prior application Serial Number 47,058, filed July 30, 1925, I disclosed an arrangement in which the housings of the instruments are provided with windows exposed to rays of light from a bulb concealed at the rear of the panel. The light entering the housings strikes the dials at the rear of the cover as well as at the rear of the face plate if a face plate is employed. The instruments are thus indirectly lighted and there is no glare.

While satisfactory illumination may be secured in this manner, I have found that the projection of light upon the dials from one direction only gives uneven lighting, producing bright patches and shadows which are disturbing to the eye. To overcome this difficulty I have, in effect, provided two sources of light each of which projects light upon the instrument dials, thus eliminating the objectionable shadows and giving, soft, even illumination. Rather than employ two actual sources of light, I use a reflector in combination with a single source, the reflector being so designed as to project light into the instrument casing from a different direction as if from another source.

In the drawings

30 Figure 1 is a rear view of an instrument panel of the type used upon automobiles showing my invention applied thereto, parts being broken away to show details of construction.

35 Figure 2 is a section on line 2-2 of Figure 1, and

Figure 3 is a diagrammatic view indicating the distribution of light upon the instrument dials.

40 I have indicated at 2 a portion of a conventional instrument panel such as is used upon automobiles. Such panels are commonly constructed of metal or wood and support the instruments in a convenient position for reading. At the right of the panel I have shown speedometer 4, at the center an assembly consisting of a motor temperature indicator 6, a meter 8, oil gauge 10, and clock 12; at the left the switch assembly 14. 45 Obviously the arrangement may be varied as desired. The instruments are secured to the panel by clamps 16, carried by bolts 18, the headed ends of which are received in stampings 20 welded or riveted to the panel.

50 Between the speedometer and the center

assembly I have mounted a reflector 22, of the shape shown most clearly in Figure 3. The reflector is apertured at 24 and provided with a clip 26 for receiving lamp socket 28 carrying bulb 30. The aperture 24 is of sufficient size to permit withdrawal of the bulb and socket from the rear of the instrument panel for inspection or replacement. The housing 32 of the speedometer 4 is provided with spaced arcuate apertures 34 and 36, covered with transparent material such as pyralin to admit light to the instrument dials, indicated at 38, preferably at the rear of face plate 40 as well as at the rear of the usual glass cover 42. The casing 44 which houses the center assembly is likewise provided with a window 46 through which light may pass to the dials.

With the described construction it is obvious that the light falling upon the dials is in part direct rays from the bulb and in part reflected rays as clearly shown in Figure 3. The reflected rays striking the speedometer dial come roughly as if from an apparent source located in the region α . If desired the reflector could be designed with mathematical accuracy so that there would be a theoretical point from which the reflected rays would appear to emanate. However, inasmuch as diffused light is preferred to a concentrated beam, the illustrated arrangement has been chosen.

It is apparent that my invention is adapted to use in other places than upon automobile instrument panels and that various modifications are contemplated as indicated by the character of the appended claims.

I claim:

1. The combination of an instrument panel, an instrument mounted on the panel comprising a housing including a portion extending rearwardly of the panel, said last named portion being apertured at separated points to permit the passage of light into the housing for the illumination of the dial, a light source at the rear of the panel arranged for the projection of light upon the dial through one of said apertures and a reflector associated with said light source and arranged to project light into said housing through another of said apertures from a different angle to produce even illumination.

2. The combination of an instrument panel, an instrument mounted on the panel

and having indicating means, said instrument being provided with a casing having a window therein for the display of the indicating means, and a plurality of spaced windows normally exposed at the rear of the panel for the projection of light from an outside source upon the indicating means, transparent covers for said windows, a light source arranged at the rear of the panel in position to direct light through one of the said spaced windows, a reflector associated with the light source and arranged to project light through the other of said spaced windows.

15 3. The combination of an instrument panel, an instrument mounted on the panel and having indicating means, said instru-

ment being provided with a casing having a window therein for the display of the indicating means, and a plurality of spaced windows normally exposed at the rear of the panel for the projection of light from an outside source upon the indicating means, transparent covers for said windows, a reflector at the rear of the panel snugly fitting the casing adjacent said spaced windows, a light source mounted in the reflector, said reflector and light source co-operating to direct light through said spaced windows from a number of different directions to give even illumination of the dial.

In testimony whereof I affix my signature.

JOSEPH ZUBATY.
